COMBINED BEVERAGE DISPENSER AND WARMER

David Charles McElroy, Detroit, Mich., assignor to The Seeburg Corporation, Chicago, Ill., a corporation of Pennsylvania

Filed Mar. 28, 1960, Ser. No. 59,883

Term of patent 14 years

(Cl. D2—3)

Fig. 1

Fig. 2

FIG. 1 is a perspective view of a combined beverage dispenser and warmer embodying my new design;

FIG. 2 is a similar perspective view of the same as seen from the side opposite that shown in FIG. 1.

The rear, not shown, is substantially without ornamentation.

The dominant features of the design reside in the portions shown in full lines.

I claim:

The ornamental design for a combined beverage dispenser and warmer, as shown and described.
